US0D1021533S

(12) **United States Design Patent** (10) **Patent No.:** **US D1,021,533 S**
(45) **Date of Patent:** **** Apr. 9, 2024**

(54) **USER INTERFACE FOR A MICRO PUREE MACHINE**

3/134; A21B 3/135; A21B 3/155; A23N
12/10; A23B 4/052; B01F 27/91

See application file for complete search history.

(71) **Applicant:** **SharkNinja Operating LLC**,
Needham, MA (US)

(56)

CLAIM

The ornamental design for a user interface for a micro puree machine, as shown and described.

DESCRIPTION

FIG. 1 is a top, front, left side perspective view of a user interface for a micro puree machine, showing our new design;

FIG. 2 is a front elevation view thereof;

FIG. 3 is a left side elevation view thereof;

FIG. 4 is a right side elevation view thereof;

FIG. 5 is a top plan view thereof;

FIG. 6 is a bottom plan view thereof; and,

FIG. 7 is a top, front, left side perspective view of the user interface for a micro puree machine in use.

The broken lines in the drawings illustrate features and environment that form no part of the claimed design.
